UNITED STATES PATENT OFFICE.

TRAUGOTT GOLDE, OF GERA, GERMANY, ASSIGNOR TO GOLDE PATENT MANUFACTURING COMPANY G. M. B. H., OF GERA, GERMANY.

HINGED VEHICLE-HOOD.

1,092,352.

Specification of Letters Patent.

Patented Apr. 7, 1914.

Application filed November 25, 1912. Serial No. 733,274.

To all whom it may concern:

Be it known that I, TRAUGOTT GOLDE, a citizen of Germany, residing at Gera, in the Principality of Reuss, Younger Line, Germany, have invented a new and Improved Hinged Vehicle-Hood, of which the following is a specification.

This invention relates to a hinged vehicle hood of novel construction, which may be readily manipulated and which insures an extremely firm and reliable support for the top when the latter is unfolded.

In the accompanying drawing: Figure 1 is a side view of a vehicle hood embodying my invention; Fig. 2 a side view partly folded and with the top omitted; Fig. 3 a similar side view completely folded; Fig. 4 a section on line 4—4, Fig. 1, and Fig. 5 a perspective view of part of the front bow and adjoining parts.

The hood is shown to comprise a pair of back bows 10, 11 to the foremost bow 11 of which is pivoted at 12, a forwardly extending arm 13 to which, in turn is pivoted at 14 the outrigger bow 15.

From the inner side of arm 13, there depends a lug 16 pivoted at 17 to the reduced shank 18 of the front bow 19. At its lower end, shank 18 is stepped as at 20 and the free end of this step is in turn bent sidewise and upward to form an integral U-shaped bearing or keeper 21. To the outer face of step 20 which is located in the same vertical plane as the outer face of lug 16, there is pivoted at 22, some distance back of keeper 21, one end of a brace 23, the other end of which is pivoted at 24 to bow 11, said brace occupying substantially the same vertical plane as arm 13 (Fig. 4).

The foldable top 25 of the hood is supported by the rear bows 10, 11, the front bow 19 and the outrigger bow 15.

When the hood is unfolded (Fig. 1) brace 23 forms a straight rearward continuation of bow 19, its forward end overlying step 20 and being grasped by keeper 21. In this way, an extremely firm and reliable support for the front bow is obtained, so that the stability of the hood is insured. When the device is being folded, the lower end of bow 19 will swing downward, so that keeper 21 will release brace 23 (Fig. 2) and the latter will swing upon step 20 into substantial parallelism with arm 13 (Fig. 3), the step in the front bow-shank permitting said front bow to be placed alongside arm 13 and brace 23.

I claim:

A vehicle hood comprising a rear bow, an arm pivoted thereto, a lug depending from the arm, a front bow having a shank of reduced thickness which is pivoted to the lug and is provided with a step and a U-shaped bearing at such step, and a brace pivoted to said rear bow and shank-step and occupying substantially the same vertical plane as the arm, said brace being adapted to engage the bearing when the hood is unfolded, the step in the shank permitting the front bow to be placed alongside the arm and brace when the hood is folded.

TRAUGOTT GOLDE.
